UNITED STATES PATENT OFFICE.

GEORGE HOLMES COCKS, OF ADRIAN, MICHIGAN.

NUT-LOCK.

1,379,394.

Specification of Letters Patent.

Patented May 24, 1921.

Application filed September 18, 1920. Serial No. 411,241.

To all whom it may concern:

Be it known that I, GEORGE HOLMES COCKS, a citizen of the United States, residing at Adrian, in the county of Lenawee 5 and State of Michigan, have invented certain new and useful Improvements in Nut-Locks, of which the following is a specification, reference being had to the accompanying drawings.

10 This invention relates to nut locks, and particularly to that class of nut locks wherein a key is disposed within a key seat formed in the bolt and engages the nut to prevent the accidental removal of the nut unless the 15 key be withdrawn.

The general object of my invention is to provide a very simple and cheaply constructed nut lock which may be used with standard bolts and nuts and requires no 20 special construction of the nut or of the bolt other than the formation of the ordinary key seat in the bolt.

A further object is to provide a nut lock of this character in which the key has a 25 long bearing against the sides of the key seat and in which the key or lock may be readily removed or replaced and used a large number of times without any injury to the nut lock or to the bolt and nut.

30 Other objects will appear in the course of the following description.

My invention is illustrated in the accompanying drawings, wherein:—

Figure 1 is an elevation of a shaft and 35 nut with my nut lock applied thereto;

Fig. 2 is a sectional view through the shaft and nut showing my nut lock applied thereto;

Fig. 3 is an end elevation of the shaft, nut 40 and nut lock;

Fig. 4 is a side elevation of the nut lock.

In these drawings, 10 designates a bolt, shaft or like member which is screw-threaded with standard threads 11 and 45 which is formed with a longitudinally extending key seat 12, the nut 13 being of ordinary form.

The key or lock is designated generally 15 and is made of spring steel. This member 50 15 is bent so as to form a portion 16 which extends approximately parallel to the axis of the bolt when the device is in use, the clip 15 being then bent around and overhanging this portion 16, as at 17. The portion 55 16 is corrugated or bent so as to form a section of a screw-thread corresponding in

number to the threads on the nut designed to be used with the bolt 10 and corresponding in pitch to these threads, in other words these bends or corrugations in the portions 60 16 are intended to fit standard screw-threads such as are used on standard nuts and bolts. It will be understood, of course, that there is a standard of threads for each size nut. Thus a $\frac{3}{8}$ " nut 16 threads to the 65 inch, a $\frac{1}{2}$ " nut 13 threads to the inch, a $\frac{5}{16}$ " nut 11 threads to the inch, a $\frac{3}{16}$ " nut 10 threads to the inch, and so on. The sizes of the key seat in the shaft or like member are standard for different sizes of shafts. Thus for a 1" 70 shaft, the key seat is $\frac{5}{16}$ " and, therefore, the key 15 for a 1" nut would have a width of $\frac{5}{16}$ " and 8 threads to the inch, which are standard for 1" nuts, and so on, the width of the key and the number of threads to the 75 inch varying with the sized nut to be used and the sized key which is used.

In the use of this device, the nut is placed upon the shaft or other member 10 and tightened up. The spring clip or key is then slid 80 into the key seat and the corrugated portion 15 will slide over the thread on the nut left bare by the key seat. When the arm 17 of the key engages the side face of the nut 14, the resilience of the spring metal key will 85 cause the notches or corrugation in the portion 16 to fit into and engage with the thread of the nut. Thus the clip or key is held from sliding off the shaft and nut by the corrugation at one end of the key. Thus the key is 90 held in such engagement with the nut that if the nut 13 is to turn, the edge of portion 16 of the key will bear against the side wall of the key seat while the other edge will bite into the nut threads and the nut will be held 95 from turning. When it is desired to remove the nut or release it, it is only necessary to pull out forcibly on the clip or key, whereupon the arm 17 will slide off of the face 14 and the part 16 will free itself from the bevelled threads in the nut and the clip is removed. Then the nut may be unscrewed. It is obvious that this clip or key may be inserted and replaced any number of times without injury. It will also be seen that the 100 nut does not have to be turned around to a certain definite place to lock the nut, but that one-sixth of a turn, where the nut is hexagonal, will lock the nut.

It will be noted that the key has a relatively long bearing against the sides of the key seat and that the key or locking device

is very simple, may be very cheaply made, and that it does not require to be made with great exactness or delicacy.

What I claim is:—

- 5 1. The combination with a screw-threaded member and a nut engaging therewith, the screw-threaded member having a longitudinally extending key seat, of a key for the nut comprising a strip of resilient metal bent upon itself to provide a portion adapted to be inserted in said key seat, and a portion adapted to bear upon the outside face of the nut, the portion inserted within the key seat having corrugations approximately fitting the threads of the nut, the resilience of the key when in place causing this corrugated portion to bear against the threads of the nut.
- 10 2. The combination with a screw-threaded member having a longitudinally extending key seat and a nut engaging the screw-threaded member, of a locking device for the nut comprising a strip of resilient metal bent upon itself to provide a portion adapt-

ed to extend along the key seat and having 25 a width approximately the same as the key seat and corrugated to fit the threads of the nut, and a resilient portion adapted to extend over and engage the outer face of the nut, the two portions being urged toward 30 each other to resiliently grip against the inner and outer faces of the nut by the resilience of the material from which the locking device is made.

3. A locking device for nuts comprising 35 a strip of resilient metal bent to provide a portion adapted to be inserted within a key seat formed in a screw-threaded member, and a portion adapted to engage upon the exterior face of a nut, said first-named portion being formed with a plurality of corrugations adapted to fit the threads of a nut and said portions being urged toward each other by the resilience of the metal from 40 which the locking device is made.

In testimony whereof I hereunto affix my signature.

GEORGE HOLMES COCKS.
